(57) **CLAIM**

The ornamental design for a display panel of a programmed computer system with a graphical user interface, as shown and described.

DESCRIPTION

FIG. 1 is a front view of a first state of a first embodiment of a display panel of a programmed computer system with a graphical user interface;

FIG. 2 is a front view of a second state thereof;

FIG. 3 is a front view of a third state thereof;

FIG. 4 is a front view of a fourth state thereof;

FIG. 5 is a front view of a first state of a second embodiment;

FIG. 6 is a front view of a second state thereof;

FIG. 7 is a front view of a third state thereof;

FIG. 8 is a front view of a first state of a third embodiment;

FIG. 9 is a front view of a second state thereof;

FIG. 10 is a front view of a third state thereof;

FIG. 11 is a front view of a fourth state thereof;

FIG. 12 is a front view of a fifth state thereof;

FIG. 13 is a front view of a sixth state thereof;

FIG. 14 is a front view of a first state of a fourth embodiment;

FIG. 15 is a front view of a second state thereof;

FIG. 16 is a front view of a third state thereof; and,

FIG. 17 is a front view of a fourth state thereof.

The outermost broken line rectangle illustrates a display panel and forms no part of the claimed design. The remaining broken lines illustrate portions of the graphical user interface that form no part of the claimed design.

In the first embodiment, the appearance of the transitional image sequentially transitions between the images shown in FIGS. 1-4. In the second embodiment, the appearance of the transitional image sequentially transitions between the images shown in FIGS. 5-7. In the third embodiment, the appearance of the transitional image sequentially transitions between the images shown in FIGS. 8-13. In the fourth embodiment, the appearance of the transitional image sequentially transitions between the images shown in FIGS.

(Continued)

14-17. In each case, neither the process by which one image transitions to another image nor the period over which the transitions occur form a part of the claimed design.
